HONING MACHINE

Harold L. Blood, Worcester, Mass., assignor to The Heald Machine Company, Worcester, Mass., a corporation of Massachusetts

Application September 23, 1936, Serial No. 102,147

14 Claims. (Cl. 51—95)

The present invention relates to a honing machine and particularly to a machine for the successive honing of a plurality of similar workpieces, all to the same predetermined finished dimension.

In prior devices of this character the honing operation has generally removed such a relatively small amount of material from the workpiece that it has been considered unnecessary to control the finished size by a size-controlling device, especially when the workpiece has been accurately machined before honing. Where the dimension of the honed workpieces must be accurately controlled, within close limits however, a size-controlling device has been found desirable and one of the principal objects of the present invention is, accordingly, to provide a size-controlling mechanism in a honing machine so that the honing operation will be brought to a close when the workpiece has been honed precisely to a predetermined dimension.

In applicant's prior copending application, Serial No. 100,911 filed Sept. 15, 1936, is disclosed a hone structure in which the wear on the honing members is automatically compensated for by a mechanically actuated device which is entirely automatic and operates independently of the individual honing operations on successive workpieces so that compensation for wear on the honing members occurs only when necessary and independent of the number of workpieces honed. This type of compensation, in general, is entirely satisfactory, although where a honing machine is controlled and actuated by fluid pressure actuated mechanisms it is desirable to provide a fluid pressure actuated mechanism for compensating for the wear on the hones. Thus, a further feature of the present invention is the provision of a fluid pressure actuated mechanism by which to procure a compensation for wear on the individual honing members only when such a compensation becomes necessary, and independently of the number and length of the honing operations between successive compensatory adjustments.

In order to prevent damage to the honing members, which are generally in the form of stones of abrasive material, it is desirable to withdraw the honing members radially of the hone to move the members out of engagement with the workpiece before the hone is withdrawn axially from the workpiece. This is true in the honing of either internal or external surfaces of workpieces and in the honing of cylindrical bores the hone must be contracted to permit its entry within the un-honed bore without damage to the honing mem-

bers. A further feature of the present invention resides in the provision of a mechanism for automatic expansion and contraction of the hone automatically in predetermined relation to the relative axial movement of the hone and workpiece which brings the workpiece into operative relation with the hone and withdraws it therefrom.

Other and further objects and advantages of the invention will hereinafter more fully appear from the following detailed description taken in connection with the accompanying drawings in which—

Fig. 1 is a side elevation of a machine embodying the invention, with parts broken away to show certain features.

Fig. 2 is a vertical sectional view through a part of the machine of Fig. 1, showing the hone in operative position.

Fig. 3 is a fragmentary vertical section showing parts of the table controlling and actuating mechanism therefor.

Fig. 4 is a vertical sectional view corresponding to Fig. 2, but showing the gage within the bore of the workpiece.

Fig. 5 is a side elevation of a detail with parts in section.

Fig. 6 is a horizontal sectional view along the line 6—6 of Fig. 2.

Fig. 7 is a horizontal sectional view substantially along the line 7—7 of Fig. 1.

Fig. 8 is a fragmentary vertical section along the line 8—8 of Fig. 7.

Fig. 9 is a fluid pressure diagram.

Fig. 10 is a vertical sectional view of a modified form of the structure which supports and controls the hone.

Fig. 11 is a fragmentary sectional view of a part of the mechanism of Fig. 10.

Fig. 12 is a horizontal sectional view along the line 12—12 of Fig. 10.

Fig. 13 is a fragmentary fluid pressure diagram for the structure of Figs. 10 to 12.

Like reference characters refer to like parts in the different figures.

With reference to Fig. 1, the machine, which discloses one embodiment of the invention, comprises a base 1 having a standard 2 and a horizontal extension 3, in the upper end of which is journaled a spindle 4 carrying a hone 5. The workpiece *a* is mounted in a suitable chuck 6 of any desired character, and the chuck is carried by a bracket 7 forming part of a reciprocating table 8. The latter is mounted for vertical reciprocation on guideways 9, Fig. 7, provided by the 55

standard 2, and the workpiece is in axial alignment with the hone, the table being moved upwardly to cause the hone to enter within the bore of the workpiece and procure a honing operation thereon.

The table is reciprocated preferably by fluid under pressure and as shown in Fig. 2, the mechanism comprises a cylinder 10 secured within the standard 2 and having a piston 11, whose outwardly extending piston rod 12 is secured to a lug 13 on the table. Fluid under pressure is alternately directed to opposite ends of the cylinder for procuring the vertical reciprocatory movement of the table by means of a reversing valve 14, the position of which is controlled by a pilot valve 15, Fig. 3, hereinafter more fully described. The pilot valve is shifted for reversing the direction of the table movement by means of a reversing lever 16, Fig. 3, in the form of a bell crank lever, one end of which engages with the projecting end of the pilot valve. The opposite end of the bell crank lever extends into alignment with reversing dogs 17 and 18 on the table which alternately engage and rock the reversing lever. When the hone is in operative engagement with the workpiece the latter is vertically reciprocated over the hone with the reversing dogs determining the opposite ends of the reciprocatory movement.

When the honing operation is completed the reversing dog 18 is rendered inoperative and allows the table to have an extended downward movement into the position of Fig. 1 for withdrawing the hone from the workpiece bore. With reference to Figs. 2 and 3, the reversing dog 18 is carried on the end of a horizontally slidable rod 19, which, when the honing operation is completed, is moved to the left (from the position shown) under the influence of a gage hereinabove described, and this movement of the shaft 19 procures turning movement of the dog 18 on its pivot pin 20 as a result of engagement between a projecting arm 21 on said dog and a pin 22 mounted in the table 8, so that the dog assumes the position of Fig. 4 out of alignment with the reversing lever.

The gage 23 is in the form of a plug positioned in alignment with the workpiece bore and adapted to enter the end thereof when the latter is honed to the desired size. The gage is carried on the end of a rod 24 vertically slidable in the bracket 7 and said rod has a conical collar 25 thereon for effecting movement of the rod 19. The left hand (Fig. 2) end of the rod 19 is enlarged and has a slot 26 through which the rod 24 extends and an adjustable screw 27 projecting into the slot is in a position for engagement with the collar 25 as the latter is carried upwardly by entry of the gage within the workpiece.

The gage is normally urged upwardly toward the workpiece by a coil spring 28 surrounding the rod and located between the collar 25 and a projecting bearing 29 integral with the table. The rod 24 has at its lower end, an enlarged head 30 positioned within a cup 31 secured to the base 1 and vertically adjustable therein. The cup has a central opening 32 for the rod 24. In the arrangement shown the base has a threaded bore 33 for engagement with the threads 34 on the lower end of the cup 31. The inwardly extending flange 35 at the opening 32 at the upper end of the cup engages with the head 30 to limit the upward movement of the gage as the workpiece moves upwardly into operative position.

When the workpiece is in operative position

and is shifted vertically upward, (causing a relative movement of the hone toward the lower end of the workpiece), the gage is drawn away from the workpiece to avoid engagement between the gage and the end of the hone. As the workpiece moves downwardly in operative position, the gage is allowed to move into contact with the end of the workpiece and when the workpiece is honed to the desired size the gage enters therein. When this occurs, the parts assume the position of Fig. 4, with the collar 25 engaging with the adjustable screw 27 procuring the above mentioned movement of the shaft 19 to the left and rendering the reversing dog 18 inoperative, thereby withdrawing the workpiece from engagement with the hone.

After the finished workpiece has been removed from the machine and an un honed workpiece placed in the workholder, the gage is unable to enter the un honed bore and is restored to the position of Fig. 1 relative to the workpiece, thereby moving the collar 25 downwardly out of engagement with the screw 27. The shaft 19 is then returned to the position of Figs. 1 and 2 by means of a coil spring 36 surrounding the rod 19 between a bracket 37 secured to the table, and adjustable nuts 38 on said shaft. The nuts 38 limit the movement of the rod 19 to the right by engagement with a portion of the table and thereby control the operative position of the reversing dog. The dog is moved into the position of Figs. 2 and 3 in readiness for the subsequent operation by a cam 39 on the standard 2, which, during the movement of the table upwardly into operative position, engages with the arm 21 on said dog and procures turning movement of said dog on its pivot pin 20.

With reference to Fig. 2, the hone 5 which is adapted for expansion and contraction, is made up of a plurality of honing stones 40 suitably secured to carriers 41 located in radial slots 42 in a sleeve 43 secured to the spindle 4. Flat springs 44 attached to the sleeve 43 at opposite ends of each of the carriers 41 hold the latter within the slots and normally urge said holders inwardly against the conical end 45 of a rod 46 axially slideable within the spindle 4 and sleeve 43, said rod, by its axial movement procuring expansion or contraction of the stones.

The spindle 4, which is journaled in the horizontal extension 3 of the standard, has secured thereto, as by a key 47, a ring gear gear 48 engageable with a pinion 49 on the end of a shaft 50 journaled in the extension 3 and connected to a driving motor 51, Fig. 1, which provides for rotation of the hone, and also for rotation of a fluid pressure pump 52 located between the motor and the pinion.

The rod 46 is axially slideable within the spindle 4 and has a key 53 movable in a keyway 54 in the shaft to provide for axial movement of said rod without turning movement relative to the spindle. The downward movement of the rod 46, which procures expansion of the stones, is limited by a nut 55 in threaded engagement with the rod and engaging with the upper end of the sleeve or spindle 4. The upper end of the rod 46 carries a piston 56 movable in a cylinder 57 in a housing 58 mounted on the extension 3 and coil springs 59 positioned between the upper side of the piston and the end of the cylinder urge the rod 46 resiliently downwardly for expanding the hone into engagement with the workpiece bore. Fluid under pressure is admitted to the underside of the piston 56 through a suitable conduit 60, at

the end of the honing operation, to provide for contraction of the hone so that the latter will be withdrawn radially from engagement with the workpiece and may be of small enough diameter 5 to enter the unfinished bore of the successive workpiece.

To compensate for wear on the honing stones the nut 55 is turned slightly on the rod 46 when compensation is necessary so that during the successive honing operation the hone carriers 41 will be moved a slightly greater distance outwardly by reason of the slightly greater downward movement of the rod 46. For this purpose the rod 46 has journalled thereon, directly above the nut 55, 10 a collar 61 which has ratchet teeth 62, Figs. 1 and 9, cooperating with correspondingly formed teeth 63 on the upper end of the nut 55. The collar 61, as best shown in Fig. 6, has a segmental recess 64 in which is received the end of a pin 65 projecting from the rod 46, so that the collar 61 may turn relative to the rod 46 through a small angle. The collar 61 is normally held in the position of Fig. 6, relative to the rod 46 by a coil spring 66 positioned within the recess.

25 When the hones are reduced in size by wear so that a compensation for wear is required, a fluid pressure actuated plunger 67, Fig. 2, slideable in a recess 68 in the housing 58, in which the cylinder 57 is located, engages with the collar 61 to hold 30 the latter against turning movement. With the rod 46 turning in the direction indicated by the arrow, Fig. 6, and with the collar 61 held against turning movement, it will be apparent that the nut 55 will be turned on the rod 46 a predetermined amount, controlled by the length of the segmental recess 64, and will accordingly allow 35 the rod 46, during the subsequent honing operations, to move downwardly a slightly greater distance than before. After this compensation has 40 taken place and the fluid pressure on the plunger 67 has been relieved, the collar 61 is returned to the position of Fig. 6 by means of the spring 66, since the ratchet teeth are effective only in one direction.

45 The hones do not, in general, wear to such an amount that a compensation is necessary during each honing operation since only a small amount of stock is removed from the workpiece. The honing operation is preferably completed within 50 a predetermined number of reciprocatory strokes of the workpiece relative to the hone. If the honing operation takes more than this predetermined number of strokes the honing stones are not exerting enough pressure against the work and a compensation for wear is necessary. If the compensation occurs before necessary the proper surface finish is not obtained. In order that the compensation may take place only when necessary so that the honing operation may be completed within the predetermined number of reciprocations, the compensatory mechanism has been arranged to function independently of the number of honing operations performed by the machine.

55 With reference to Figs. 1 and 5, the table 8 has a projecting dog 69, which, when the table is in operative position, engages with the end of an arm 70, journalled on a stud 71, to procure oscillation of the latter. A pawl 72 is carried by the 60 end of said arm and urged by a spring 73 into engagement with a ratchet 74 journalled on the same stud 71 on the standard 2. A pin 75 in the standard 2 limits the downward movement of the arm 70 which is urged resiliently downwardly by 65 a spring 76 also mounted on the standard. The

ratchet is normally urged counterclockwise by a coil spring 77 surrounding the stud 71 and having one end engaging with a pin 78 on the standard 2, and the other end engaging in an opening 79 in the ratchet. A second pawl 80 journalled on a pin 81 on the standard 2 is held resiliently in engagement with the ratchet by a spring 82 to prevent counterclockwise movement of the ratchet.

A lug 83 on the ratchet is in a position for engagement with a projecting end of a valve 84 in a valve casing 85 secured to the standard. When the valve is shifted by the lug 83 a compensation for wear of the honing stones takes place, since fluid under pressure is directed to the recess 68 to shift the plunger 67, as will be hereinafter 15 described. The ratchet is normally in the position of Fig. 1, with the lug 83 spaced angularly a substantial distance from the end of the valve 84. For each reciprocation of the table the ratchet is advanced clockwise a predetermined number of teeth in response to the oscillation of the arm 70 by the dog 69 on the table.

If the gage enters the bore of the workpiece before the valve 84 is shifted by the lug 83 no compensation for wear takes place, and when the 25 table reaches the inoperative or loading position of Fig. 1, the ratchet is allowed to return to its original position in readiness for the subsequent honing operation. To this end the table 8 has a projecting bar 86, Fig. 1, having a shoulder 87 30 engageable with the pawl 80 to rock the latter out of engagement with the ratchet. The dog 69 is withdrawn from engagement with the arm 70 as the table moves downwardly, and the arm 70 also moves downwardly, bringing an extending arm 35 88 on the pawl 72 into engagement with a cam 89 carried by the standard 2. This cam causes withdrawal of the pawl 72 out of engagement with the ratchet so that the latter may be turned counterclockwise by the spring 77 into the normal position of Fig. 1. When the hones have become worn to such an extent that the honing operation is not completed before the valve 84 is shifted by the lug 83, a compensation for wear takes place. Thus the compensation for wear on the stones 40 takes place when necessary and independently 45 of the number of honing operations between successive compensations.

As above stated, the hones are expanded when the hone has entered the workpiece and are contracted before the workpiece is fully withdrawn from engagement therewith. With reference to Figs. 7 and 8, a valve casing 90 is mounted within the standard 2 and has a valve 91 slideable therein, Fig. 1. The valve has a projecting end 92 in a position for engagement by a cam 93 secured to the table. As the workpiece reaches operative position the valve 91 is shifted by the cam 93 to allow fluid under pressure to exhaust from beneath the piston 56, thus allowing the hone to 50 expand into operative position, and as the table moves downwardly to withdraw the workpiece from position the valve 91 is released and fluid pressure is again directed to the underside of the piston 56, thereby elevating the piston and contracting the hone. The cam 93 is preferably located in a position to procure the expansion and contraction of the hone while the workpiece is in operative honing position.

With reference to Fig. 9, which shows the fluid 70 pressure diagram in detail, the pump 52 draws fluid under pressure through a conduit 94 from the tank 95 which is positioned within the standard. Fluid under pressure from the pump 52 is directed through a pressure conduit 96 to the 75

several valve mechanisms, the pressure in this conduit 96 being controlled by a relief valve 97 in an exhaust connection 98 from the pump to the tank.

5 For controlling the table movements the pilot valve 15, which is located in the valve casing 99, controls the position of the main reversing valve 14 by which fluid is directed alternately to opposite ends of the table cylinder 10, the reversing valve 14 being located in a casing 100 attached to the table cylinder 10. The pressure conduit 96 is connected by another conduit 101 to a port 102 in the pilot valve casing 99, and fluid under pressure passes selectively from the port 102 to either of two spaced ports 103 or 104 in the casing 99, these ports being connected by conduits 105 and 106 respectively, to opposite ends of the reversing valve casing 100. The pilot valve has two spaced reduced portions 107 and 108 and when fluid under pressure is admitted to one of the ports 103 or 104 by one reduced portion, the other of these ports is connected by the other reduced portion to one of two spaced exhaust ports 109 and 110 in the pilot valve casing. These latter ports are connected by conduits 111 and 112 to the exhaust connection 98.

With the pilot valve in the position shown, which is the position of the valve during upward movement of the table, fluid under pressure passes through the conduit 106 and urges the main reversing valve 14 into the position shown so that fluid under pressure is directed to the lower end of the table cylinder. As shown, a conduit 113 provides a connection between the conduit 101 and two spaced inlet ports 114 and 115 in the reversing valve casing 100. A channel 116 in the table cylinder provides a fluid connection between an outlet port 117 in the casing 100 and the lower end of the table cylinder and a channel 118 provides a connection between an outlet port 119 in the casing 100 and the upper end of the table cylinder. An exhaust port 120 in the casing 100 is connected by a conduit 121 to the conduit 118 from the pilot valve to the exhaust connection 98. The reversing valve 14 has two spaced reduced portions 122 and 123 which provide fluid connection between the ports 114 and 119 or the ports 115 and 117 selectively, the opposite one of the ports 117 or 119 being connected to the exhaust port 120. Shifting of the pilot valve 15 will shift the reversing valve 14 and accordingly reverse the direction of movement of the table.

To prevent upward movement of the table beyond the normal operative position, the channel 118 is spaced a short distance from the extreme end of the cylinder 10, and if the piston 11 moves beyond the end of this channel the exhaust of fluid through the reversing valve is cut off. To permit downward movement of the table from a position where the piston 11 covers the end of the channel 118, a by-pass 124, having a ball check valve 125 therein, provides a connection from the channel 118 to the extreme upper end of the table cylinder to allow the entrance of fluid under pressure to the end of said cylinder.

As above stated, the valve 91 controls the expansion and contraction of the hone. Referring again to Fig. 9, the fluid pressure conduit 101 is connected to a port 126 in the casing 90 and the conduit 60, above referred to, is connected to a port 127 in the same casing. The valve 91 is normally held in the position shown by a coil spring 128, so that fluid under pressure is directed around a reduced portion 129 of said valve to the

underside of the piston 56, urging the latter upwardly and thereby collapsing the hone. As the work reaches operative position the valve 91 is shifted to the right, as above stated, closing the port 126 and providing fluid connection from the port 127 to a port 133 connected by a conduit 131 to the exhaust conduit 111, thus allowing fluid to exhaust from the cylinder 57 so that the piston can move downwardly and procure expansion of the hone for the honing operation, the expansion being limited by engagement between the nut 55 and the end of the spindle 4.

The mechanism which provides for compensation for wear is actuated by fluid under pressure, as above stated. Referring again to Fig. 9, the fluid pressure conduit 96 is connected by a short circuit 132 to a port 133 in the casing 85. A port 134 in the same casing is connected by a conduit 135 to the recess 68. The valve 84 is normally in the position shown in which the reduced portion 136 of the valve provides fluid connection between the port 134 and an exhaust port 137 connected by a conduit 138 to the exhaust conduit 111. When compensation for wear becomes necessary the lug 83 procures movement of the valve 84 to the right, allowing fluid under pressure to enter the recess 68, shifting the plunger 67 to the left to lock the collar 61 frictionally against turning movement. When the collar is held against turning the relative turning movement of the collar on the spindle (limited by the length of the segmental recess) procures a corresponding turning movement of the nut 55 on the rod 46 to allow the rod to move slightly farther downwardly during subsequent honing operations.

In operation, the machine, when at rest, is in the position of Fig. 1, in which is shown an un honed workpiece *a*, the internal diameter of which is too small to allow the gage 23 to enter therein. The gage is accordingly held in the position shown, with the collar 25 on the gage rod in such relation to the adjustable screw 27 that the rod 19 is in the right hand position of this figure. To set the machine in operation, the operator turns the handle 139, Fig. 1, which is directly connected to the reversing lever 16 and thereby procures movement of the pilot valve 15 to the left into the position of Fig. 9 for upward movement of the table into operative position. As the table moves upwardly into operative position the pivotally mounted dog 18 is engaged by the cam 39 and turned into the position of Fig. 2, for controlling the position of reciprocation of the table during the honing operation. As the table reaches operative position with the hone located within the workpiece, the hone, which has been contracted, is caused to expand by the shifting movement of the valve 91.

The hone having entered the bore of the workpiece and been expanded, the workpiece is reciprocated in operative position until, during a downward movement of the table, the gage 23 enters the workpiece bore, thereby procuring movement of the rod 19 to the left to render the reversing dog 18 inoperative. The table then begins its downward movement into inoperative position. As the table begins its downward movement into inoperative position, and before the hone is entirely withdrawn from the workpiece bore, the cam 93 releases the valve 91 so that the latter returns to the position of Fig. 9 and causes a contraction of the hone.

During the honing operation, while the table is reciprocated in operative position, the reciprocations procure a step-by-step clockwise advance

of the ratchet 74. If the honing stones are not worn to such an extent as to require adjustment of the hone, the honing operation will be brought to an end by entry of the gage in the workpiece bore before the lug 83 is brought into engagement with the valve 84 and no compensation for wear takes place. As the table moves downwardly into inoperative position at the end of each honing operation, the ratchet 74 is released and returned by the spring 77 to its original position of Fig. 1 in readiness for the subsequent honing operation.

If there is a necessity for compensating for wear on the hone, the reciprocations of the table procure a clockwise rotation of the ratchet 74 far enough to procure shifting movement of the valve 84 by the lug 83, thereby introducing fluid under pressure to the right hand end of the plunger 67. When this occurs, the collar 61 is frictionally held against turning until the nut 55 has been backed away on the rod 46 far enough to allow the honing stones to move radially outward to compensate for the amount they have been reduced in size. When compensation for wear occurs, the honing operation proceeds as before, with the lug 83 withdrawn from the valve 84 as the result of the downward movement of the table at the end of the honing operation, so that the plunger 67 is backed away from the collar 61 until a further compensation for wear becomes necessary.

In the modification of Figs. 10 to 13 inclusive, the compensation for wear on the honing stones is provided in a somewhat different manner than that above described. With reference to these figures, the hone spindle 4' has secured thereto a sleeve 43' within which the hone actuating rod 46' is slideable. The spindle 4' has secured thereto the driving gear 48' for rotation of the hone 5' on the end of the sleeve 43'. A nut 55' is in threaded engagement with the rod 46' and engages the end of the spindle 4' to limit the downward movement of the rod 46' and thereby control the expanded position of the honing stones. To the upper end of the rod 46' is secured a piston 56' vertically slideable in a cylinder 57'. Coil springs 59' engage with the upper side of the piston 56', normally urging the piston downwardly for expanding the hones. Thus far the structure is the same as that of the original embodiment of the machine above described.

To provide for the compensation for wear in this modification, the housing 58' has positioned above the cylinder 57' a slightly larger cylinder 140 in which is positioned a piston 141 directly above the piston 56'. Fluid under pressure is normally directed to the upper side of the piston 141 through a conduit 142, thereby holding the piston 141 in its lower position of Fig. 10 to limit the upward movement of the rod 46'. The spindle 4' has an integral sleeve 143 surrounding and extending above the nut 55', and within the sleeve is positioned a collar 144 having ratchet teeth 145 cooperating with corresponding ratchet teeth 146 on the nut 55'. A shoulder 147 on the collar engages the end of the sleeve 143 and normally holds the cooperating ratchet teeth out of engagement.

When a compensation for wear becomes necessary, the fluid under pressure above the piston 141 is allowed to exhaust, thereby allowing the piston 56' to move upwardly far enough for the cooperating ratchet teeth to engage with each other. A continued upward movement of the rod 46' after the teeth are in engagement pro-

cures a rotation of the collar 144 relative to the rod 46', since this collar has a slot 148, Fig. 12, engageable with a pin 149 projecting from the rod 46'. The slot 148, however, extends at an angle to the center line of the rod 46' to produce a slight turning movement of the collar 144 which results in a corresponding movement of the nut 55' on the rod 46'. The backing off or turning of the nut 55' allows the rod to move downwardly a slightly greater distance than before, to procure an increased expansion of the hone which compensates for wear on the honing stones.

With reference to Fig. 13, the valve casing 85' corresponds to the casing 85, above described, with the exception that the port 133' is connected to the exhaust conduit 138' instead of the fluid pressure supply, and the port 137' is connected to the pressure supply conduit 132' rather than to exhaust. Thus, with the valve 84' in its normal position, fluid under pressure is directed at all times through the conduit 142 to the upper side of the piston 141. When compensation for wear on the stones becomes necessary, the valve 84' is shifted to the right, as above described in connection with the valve 84, and the piston 141 is allowed to move upwardly to permit the compensation for wear to take place.

From the foregoing, it will be apparent that the present invention relates to a honing machine in which the size of the workpiece is under the control of a sizing device, so that successively honed workpieces may all be reduced to the same size. When the honing stones become worn, the machine of the present invention incorporates a structure by which to compensate for the wear on these stones, independently of the individual honing operations. The machine also provides a hydraulically actuated mechanism by which to collapse the hone before its withdrawal from the bore of the workpiece and to provide for expansion of the hone when the latter is in a position for honing.

I claim,

1. In a honing machine, a hone comprising a plurality of angularly spaced honing members movable relative to each other and simultaneously engageable with a single surface of a workpiece, a work-support having a workpiece positioned therein for engagement by the hone, a gage for terminating the honing operation when the workpiece reaches a predetermined size, and means for compensating for wear on the hone.

2. In a honing machine, a hone comprising a plurality of angularly spaced honing members movable relative to each other and simultaneously engageable with a single surface of a workpiece, a work-support having a workpiece positioned therein for engagement by the hone, a gage for terminating the honing operation when the workpiece reaches a predetermined size, and means for compensating for wear on the hone, said last means being operative if the gage does not become operative after a predetermined period of honing.

3. In a honing machine, a hone comprising a plurality of angularly spaced honing members movable relative to each other and simultaneously engageable with a single surface of a workpiece, a work-support having a workpiece positioned therein for engagement by the hone, a gage for terminating the honing operation when the workpiece reaches a predetermined size, and means for procuring a compensation for wear on the hone a predetermined time after the beginning of the honing operation.

4. In a honing machine, a hone comprising a plurality of angularly spaced honing members movable relative to each other and simultaneously engageable with a single surface of a workpiece, a work-support having a workpiece positioned therein for engagement by the hone, a gage for terminating the honing operation when the workpiece reaches a predetermined size, and fluid pressure actuated means for procuring compensation for wear on the hone a predetermined time after the beginning of the honing operation.
5. In a honing machine, a hone comprising a plurality of angularly spaced honing members movable relative to each other and simultaneously engageable with a single surface of a workpiece, a work-support having a workpiece positioned therein, means for procuring a relative reciprocation between the hone and work-support when the latter is in operative position, a gage for terminating the honing operation when the workpiece reaches a predetermined size, and fluid pressure actuated means for procuring a compensation for wear on the honing member after a predetermined number of reciprocations of the work-support relative to the hone.
10. In a honing machine, a hone having at least one honing member movable relative to the hone for expansion and contraction thereof, a work-support having a workpiece positioned therein, a gage adapted to enter the bore of the workpiece when the latter reaches a predetermined size for terminating the honing operation, and fluid pressure actuated means responsive to the entry of said gage for contracting the hone.
15. In a honing machine, a hone having at least one honing member movable relative thereto into and out of operative position, a work-support having a workpiece positioned therein, fluid pressure actuated means for shifting said honing member, means for limiting the movement of the member into operative position, and means for procuring a compensation for wear on the member by automatic adjustment of the limiting means.
20. In a honing machine, a hone having a plurality of honing members movable relative thereto, fluid pressure actuated means for moving said members for expanding and contracting the hone, a work-support having a workpiece therein, means for procuring a relative movement between the hone and work-support for positioning the hone within the workpiece, means responsive to said relative movement for expanding the hone when the latter is located within the workpiece bore, a gage for procuring separation of the hone from the workpiece at the end of the honing
- operation, and means for contracting the hone prior to said separation.
9. In a honing machine, a rotatable hone having a plurality of honing members movable relative thereto for expansion and contraction of the hone, means for limiting the expansion of said hone, and fluid pressure actuated means for compensating for wear on the honing members by adjustment of said limiting means.
10. In a honing machine, the combination with a collapsible hone, of a size controlling mechanism having a feeler engageable with the surface of the workpiece being honed, and means under the control of the size controlling mechanism for procuring collapse of the hone.
11. In a honing machine, the combination with a collapsible hone, of a size controlling mechanism having a feeler engageable with the surface of the workpiece being honed, fluid pressure actuated means for collapsing the hone, and means under the control of the size controlling mechanism for actuating said fluid pressure means.
12. In a honing machine, a hone comprising an arbor and a plurality of angularly spaced honing members carried by said arbor and movable relative thereto into and out of operative position, a work-support, size determining means, and means under the control of said size determining means for procuring a movement of the honing members relative to the arbor into inoperative position.
13. In a honing machine, a hone comprising an arbor and a plurality of angularly spaced honing members carried by said arbor and movable relative thereto into and out of operative position, a work-support, means for procuring a honing operation in a workpiece in said support, said honing operation including an axial reciprocation between said hone and workpiece, size determining means, and means responsive to said size determining means for procuring movement of the honing members relative to the arbor into inoperative position.
14. In a honing machine, a hone comprising an arbor and a plurality of angularly spaced honing members carried by said arbor and movable relative thereto into and out of operative position, a work-support, means for procuring a honing operation in a workpiece in said support, said honing operation including an axial reciprocation between said hone and workpiece, size determining means and means responsive to said size determining means for procuring movement of the honing members relative to the arbor into inoperative position and withdrawal of the hone from the workpiece.
